AUTOMATIC PLATEN PRINTING PRESS

Artur Büttner and Hermann Kocher, Heidelberg, Germany, assignors to Schnellpressenfabrik Aktiengesellschaft Heidelberg, Heidelberg, Germany, a corporation of Germany

Application December 24, 1954, Serial No. 477,506

Claims priority, application Germany December 30, 1953

1 Claim. (Cl. 101—299)

The present invention relates to automatic platen printing presses and particularly to a press of this type provided with means for interrupting the printing operation.

In a platen printing press, mechanism is provided for moving the platen and type bed toward and away from one another with an oscillating or reciprocating motion. For example, the type bed may be stationary and the platen reciprocated or oscillated toward and away from the type bed. While the platen is away from the type bed, a previously printed sheet is removed and a fresh sheet to be printed is positioned on the platen. The platen then moves toward the type bed and pressure is applied between the platen and a form mounted on the bed to print the sheet carried by the platen. The term "form" is herein used in a generic sense to designate type, plates, mats or other printing media which may be mounted on the type bed in any convenient manner. When faults occur in the sheet supply during printing, it is necessary quickly to interrupt the operation of the press to prevent the dressing surface on the platen from being printed or to prevent the platen from being overloaded. In a power operated press, it is not feasible to stop the press suddenly because of the momentum of the power drive. The press is therefore provided with a device for varying the stroke of the platen so that, although the press continues to run, the platen is not moved all the way toward the type bed and no printing pressure is applied. Means is provided for shifting quickly from an "on" position in which printing pressure is applied when the platen is moved toward the type bed and an "off" position in which movement of the platen toward the type bed is curtailed so that no printing pressure is applied.

Ink is applied to the form on the type bed each time the platen moves away from the bed. The inking mechanism may, for example, comprise an inking cylinder and a plurality of rollers for feeding ink to the surface of the cylinder. If the printing operation is stopped, for example because of faulty alignment of the sheets to be printed, the press nevertheless continues to run under no load conditions and the inking mechanism continues to supply ink to the form on the type bed. Because of the continued inking of the form while the press is idling, the first sheets printed when the printing operation is resumed receive too much ink and cannot be used. It thus frequently occurs that, because of repeated interruption of the printing operation, a considerable number of sheets become useless and must be thrown away as waste paper.

It is an object of the present invention to overcome this disadvantage by automatically interrupting the feed of ink to the printing form each time the printing operation is interrupted, even though the press continues to idle. Hence, when printing is resumed, the printing form is correctly inked and the waste of paper due to overinking is avoided. In accordance with the invention,

2

the automatic interruption of the ink supply when the press is idling is accomplished by simple mechanism which is virtually infallible in its operation.

In some instances, for example in starting up a press, it is desirable to permit ink to feed to the inking cylinder and the printing form, even though the press is idling. In accordance with the invention, means is provided for blocking out the automatic interruption of the ink supply when the press is shifted to idling so that the supply of ink is maintained. A further feature of the invention is that means for interrupting the ink supply is operatively connected by a resilient connection with means for shifting the press so that printing pressure is not applied to the platen. This resilient connection permits the press to be shifted to idling at any phase in its operation without damage and also permits the inking to be continued even when the press is idling, if desired. When the printing operation is resumed, the means for interrupting the ink supply is deactivated in a positive manner so as to avoid any failure in the supply of ink to the printing form.

The objects and advantages of the invention will be more fully understood from the following description and claims in conjunction with the accompanying drawings which show preferred embodiments of the invention and in which:

Fig. 1 is a diagrammatic vertical section through a platen printing press embodying the invention;

Fig. 2 is an enlargement of a portion of Fig. 1 showing additional mechanism which, because of the small scale, is omitted from Fig. 1 for the sake of clarity;

Figs. 3 and 4 are diagrammatic sections similar to Fig. 1 but with certain parts omitted and showing another embodiment of the invention in two operational positions; and

Figs. 5, 6 and 7 are views similar to Fig. 2 but show a further embodiment of the invention in three operational positions.

In Figs. 1 and 2, there is shown a printing press having a frame 1 and a platen 2 which is pivotally mounted in the frame to swing about an axis 2a so as to move toward and away from a type bed 3 on which there is mounted a printing form 3a. The platen 2 is swung about its pivot 2a with an oscillatory motion by means of a pair of toggle levers 4, each comprising a link 4a pivotally connected to the platen at 4c and a link 4b pivotally supported by a shaft 6. At their contiguous ends 4d, the links 4a and 4b are pivotally connected to each other and to a connecting rod 5 operated by a crank shaft 5a. The shaft 6 of the bell crank lever 4 is supported by an eccentric bushing 7 which in turn is rotatably mounted in the machine frame and may be swung by means of an arm 8 fixed to the bushing and a shift rod 9 which is pivotally connected to the arm 8 and extends out through an opening 9a in the frame of the machine. The rod 9 is movable in a lengthwise direction so as to swing the eccentric bushing between two positions. In one of these positions, the platen 2 is pressed against the printing form with the highest possible pressure while, in the other position, the shaft 6 is moved in a direction away from the platen so that no pressure is exerted by the platen on the printing form and preferably the platen surface does not come into contact with the form. Fig. 1 shows the shift rod 9, and consequently the eccentric bushing 7 and shaft 6, in the pressure-applying position. The shift rod 9 is releasably held in the position shown by means of a catch 9b which is released by lifting the outer end of the rod. When it is desired for the press to idle so that no printing pressure is applied between the platen and the printing form, the rod 9 is lifted to release it and shifted toward the right, as

viewed in Fig. 1, thereby rotating the eccentric bushing 7 in a counterclockwise direction and moving the shaft 6 toward the right.

The operation of the inking mechanism is also controlled by movement of the rod 9. On one end of the eccentric bushing 7 or on a collar fixed thereto, there is provided a fixed pin 10 to which there is linked a rod 11 which extends up through the machine frame to a position below the inking mechanism. A bell crank 12, pivotally mounted at 13 on the machine frame, has a forked end 12a which straddles an upper end portion of the rod 11 and is engaged by a compression spring 14 which surrounds the rod 11 and is confined by a collar 14a fixed on the rod. The spring 14 normally urges the forked arm 12a of the bell crank up against an enlarged head 27 on the upper end of the rod 11. The inking mechanism comprises an inking cylinder 18 from which ink is carried to the form in usual manner by other rollers not shown in the drawing. Ink is supplied to the inking cylinder 18 by means of a fountain cylinder 20 which receives ink from a duct 20a, a ductor 16 and transfer rollers 21 and 21a. The ductor 16 is carried by arms 16a fixed to a shaft 15 which is rotatably supported by the frame to permit the roller 16 to swing from the solid line position shown in Fig. 1 in which it picks up ink from the fountain cylinder 20 to a position to the left in which it transfers ink to the roller 21. The bell crank lever 12 has a second arm 12b which, by angular movement of the bell crank about its pivot 13, is swingable from the position shown in solid lines (Fig. 1) to a position to the left in which it lies in the path of an arm 17 fixed to the shaft 15 of the arms 16a carrying the ductor 16.

When printing is commenced, the rod 9, eccentric bushing 7, connecting rod 11 and bell crank lever 12 are all in the positions shown in solid lines in Fig. 1. The arm 12b of the bell crank 12 is out of the path of movement of the arm 17 fixed on the shaft 15 of the ductor and consequently does not interfere with the oscillation of this ductor. The ductor hence may without hindrance carry out its usual reciprocating movement between the fountain cylinder 20 and the ink-transmitting roller 21 so as to transmit the ink received from the ductor cylinder to the transfer rollers and hence to the inking cylinder 18. Oscillation of the ductor is effected in usual manner by suitable mechanism (not shown).

Fig. 1 shows the parts in position for printing. When it is desired to interrupt the printing operation, for example because of faulty alignment of the sheets to be printed, the rod 9 is lifted so as to release the catch 9b and is shifted longitudinally in the direction of the arrow 22, thereby rotating the eccentric bushing 7 in a counterclockwise direction and moving the shaft 6 toward the right (Fig. 1) so as to release pressure from the platen. Rotation of the bushing 7 moves the connecting rod 11 upwardly and, through the resilient connection provided by the spring 14, causes the bell crank 12 to turn in a counterclockwise direction so that the arm 12b comes into the path of movement of the arm 17, as indicated by the curved arrow 19. With the bell crank in this position, the arm 17 on the shaft 15, during its downward movement, strikes the end of the arm 12b of the bell crank 12, thereby locking the movement of the ductor 16 in the direction toward the fountain cylinder 20, thereby preventing the ductor from coming into contact with the cylinder. In this manner the transfer of ink from the fountain cylinder 20 to the inking cylinder 18 is interrupted. It will be understood that the ductor oscillating linkage, of which arm 17 is a part, is provided, in known manner, with a resilient connection (not shown) in order that arm 12 may prevent oscillation thereof without breaking said linkage. As the movement of the ductor 16 in a direction toward the fountain cylinder 20 is, in known manner, effected by means of a spring, the blocking of this ductor in the manner described is readily effected.

If it is desired to allow the ink to be fed during a period when the press is idling, it is necessary to cancel out the blocking of the ductor movement. For this purpose, there is arranged on the supporting pin 23 (Fig. 2) 5 of the arm 12a of the bell crank a further bell crank lever 24, 25 which is swingable within predetermined limits and normally assumes the position indicated by broken lines 24', 25'. The arm 25 is longer and heavier than the arm 24 so that the bell crank 24, 25 is biased by 10 gravity toward the position shown in broken lines. When the arm 25 is swung upwardly to the position shown in solid lines (Fig. 2), it is adapted to engage a fixed abutment 26 on the machine frame, thereby locking the bell crank 12 in the position shown in solid lines so that 15 it is out of the path of movement of the arm 17 and hence does not interfere with the normal oscillation of the ductor 16. This locking of the bell crank lever 12 in its released position is effected by swinging the arm 25 to its upper limit while simultaneously turning the 20 bell crank lever 12 against the action of the spring 14 when the rod 9 is in "idling" position. The pressure of the spring 14 tends to swing the bell crank 12 in a counterclockwise direction and thereby presses the locking arm 25 against the fixed abutment 26 so as to retain it in 25 locking position. The feeding of ink to the inking cylinder 18 is thus permitted, even when the printing operation is stopped and the press is idling.

On resuming the printing operation by pulling out the rod 9 in a direction opposite to the arrow 22, the connecting rod 11 is pulled downwardly so that the head 27 on the end of the rod strikes the arm 12a of the bell crank 12 and swings the bell crank in a clockwise direction. If the locking arm 25 has been set in locking position, as described above, the downward movement 30 of the connecting rod 11 relieves the pressure by which the locking arm 25 was frictionally held against the stop 26 and the arm 25 thereupon swings by gravity to the position indicated by broken lines at 25'. Thus, the initial state is automatically restored so that the bell 35 crank lever 12 is no longer hindered in its function and, when it becomes necessary to stop printing, the inking mechanism or the ink transfer is automatically blocked out of operation as before.

Figs. 3 and 4 show a modified embodiment of the 40 operative connections between the printing starting and stopping device and the inking mechanism. A lever 32 is fixedly mounted on a shaft 31 rotatably supported by the side wall 30 of the machine frame and, at its end, carries a roller 33 which rests on a rod 34 for starting and stopping the printing operation. The lever 32 is located inside the machine frame. On the outside of the wall 30, the shaft 31 carries an arm 35 to the outer end of which is connected the lower end of a rod 36. On the upper end of the connecting rod 36, there are provided fixed collars 37 and 38 with a spring 39 between them. An arm 40 of a two-armed lever 40, 42, pivotally supported on a fixed shaft 41, is pivotally connected to a sleeve 40a which is slidable on the rod 36 and is confined between the upper collar 38 and the upper end of the spring 39. This provides a resilient connection between the arm 40 and the rod 36 when the rod is moved in an upward direction and a positive connection when the arm is moved in a downward direction. The second arm 42 of the lever carries a hook-like projection 43 adapted to cooperate with a projection 44 on a lever 47 which is rigidly mounted on the pivotal axis 45 of the ductor 46 of the ink-feeding mechanism which is like that shown in Figs. 1 and 2. During normal printing, all the parts assume the positions illustrated in Fig. 3. The projection 43 on the arm 42 is spaced above the projection 44 of the arm 47 and hence the movement of the arm 47 and resulting movement of the ductor 46 in normal manner may thus be effected without interference.

In order to stop the printing, the rod 34 is lifted to 50 release it and pushed inwardly in the direction of the ar-

row 48, whereby printing pressure is released, as described above in connection with Figs. 1 and 2. Owing to the arcuate movement of the arm 8 to which the lower end of the lever 34 is connected, the portion of the lever engaging the roller 33 on the arm 32 is swung upwardly, thereby swinging the arms 32 and 35 in a counter-clockwise direction and lifting the connecting rod 36. Upward movement of the rod 36 acts through the collar 37, spring 39 and arm 40 to swing the arm 42 downwardly so that the projection 43 on the arm 42 is brought into the path of movement of the projection 44 on the oscillating lever 47. The projection 43 is thus engaged by the projection 44, thereby preventing the swinging movement of the lever 47 and the ductor 46 in the direction toward the fountain cylinder 49. Hence, the inking mechanism receives no further supply of ink from the fountain cylinder.

To permit the actuation of the inking mechanism so as to supply ink even when the printing is stopped, i. e. with the parts in the position shown in Fig. 4, there is provided a catch 50 which is pivotal about a fixed pin 51 on the machine frame and normally hangs by gravity in the position shown in full lines (Fig. 4). The double-armed lever 40, 42 is provided with a projecting surface 52 opposite the catch 50. By downward pressure on the arm 40 against the action of the spring 39, the lever 40, 42 can be swung so that the catch 50 may be brought into a position with its end face 53 abutting against the surface 52. The catch 50 is retained in this position by the operational pressure between the surfaces 52 and 53 produced by the spring 39. The abutment of the catch 50 with the surface 52 holds the lever 40, 42 in such position that the projection 43 lies above the projection 44 and hence does not interfere with the swinging of the arm 47. Thus, the ductor 46 may now freely oscillate between the fountain cylinder 49 and the first inking roller, even though the printing press is idling and the starting and stopping rod 34 is in the position shown in Fig. 4 so as to prevent operational pressure between the platen and the printing form.

When printing is again started, the rod 34 is pulled outwardly in a direction shown by the arrow 48. The connecting rod 36 is thereupon moved downwardly and the collar 38 engages the arm 40 so as to swing the lever 40, 42 in a clockwise direction and lift the projection 43 out of the path of movement of the projection 44 on the oscillating arm 47. The parts are thus restored to the position shown in Fig. 3. If the catch 50 has been engaged, downward movement of the connecting rod 36 relieves the pressure between the end face 53 of the catch 50 and the surface 52 on the lever 40, 42 so that the catch 50 is free to swing by gravity to the position shown in Fig. 3 and is thereby released. In this manner, the automatically acting connection between the printing start-and-stop rod on the one hand and the inking mechanism on the other hand becomes fully effective again so that, with each successive stopping of the printing, the inking mechanism is automatically put out of operation.

The interruption of the ink supply may, of course, be effected by acting on other parts of the inking mechanism. A further possibility is illustrated diagrammatically in Figs. 5 to 7 according to which the ink supply is interrupted by swinging a friction roller 60 out of its normal operating position. The friction roller 60 is, for this purpose, carried by levers 62 which are pivotal about an axis 61. One of the levers 62 is provided with a second arm 63 which is connected by a link 64 with one arm of a double-armed lever 65 pivotally mounted at 65a on the machine frame. The other end of the lever 65 is resiliently connected in the manner described in connection with the previous embodiments with a connecting rod 66 which in turn is connected in any desired manner with the device for starting and stopping the printing operation. When printing has been stopped, the friction roller 60 assumes a position in which it is swung out of its nor-

mal operating position, as indicated in Fig. 5. When printing has been started (Fig. 6), the friction roller 60 is swung into operational position in which it engages a second friction roller 67 and the inking cylinder 68 so as to deliver to the inking cylinder the ink that has been supplied by the preceding cylinders. Arranged below the lever 65, there is a pivotal catch 69 which normally hangs downwardly by gravity, as shown in Figs. 5 and 6. With the printing operation stopped, the lever 65 may be swung against the spring pressure of the resilient connection with the rod 66 (in a manner similar to that described above and the friction roller may thereby be brought into operating position. The catch 69 may then be swung upwards to the position shown in Fig. 7 in which it abuts against a stop surface 70 on the lever 65. The catch 69 thereby holds the lever 65 in a position to permit the feeding of ink to the inking cylinder 68 and the spring pressure exerted by the resilient connection between the lever 65 and the rod 66 retains the catch 69 in locking position. When printing is again started, the lever 65 is engaged by the upper collar on the end of the connecting rod 66, thus releasing the pressure between the catch 69 and stop surface 70 and permitting the catch to drop automatically to its released position, as shown in Figs. 5 and 6. Hence, the mechanism is in condition automatically to stop the feeding of ink whenever printing is stopped and to resume the feeding of ink when printing is again started.

The embodiments of the invention illustrated in the drawings and particularly described above are intended to illustrate, rather than limit, the invention and it will be appreciated by those in the art that various modifications may be made without departing from the invention. For example, in place of purely mechanical connections between the printing starting and stopping device and the inking mechanism, it is possible to employ electrical or electromechanical devices utilizing known instrumentalities such as positively actuated switches, electromagnets, etc. Moreover, the interruption of the ink supply may be effected at other points, for example by disengaging the connection of the fountain cylinder.

What we claim and desire to secure by Letters Patent is:

In an automatic platen printing press, a type bed adapted to have a form mounted thereon, a platen, a toggle lever system for applying pressure between said platen and a form mounted on said bed, shift means for rendering said pressure-applying system ineffective, said shift means being movable between an "on" position in which said pressure-applying system is effective and an "off" position in which said pressure-applying means is ineffective, an inking cylinder for applying ink to a form mounted on said type bed, means for supplying ink to said cylinder including a movable inking roll, latch means movable between latching and released positions for releasably holding said roll in an inactive position and thereby interrupting the supply of ink to said cylinder, operative connections between said latch means and said shift means including a resilient connection actuated by said shift means for biasing said latch means toward said latching position when said shift means is moved to "off" position, and means for selectively locking said latch means in said released position against force exerted by said resilient connection when said shift means is moved to "off" position, said locking means being gravity biased toward a releasing position and retained in a locking position by said resilient connection so that upon moving said shift means to "off" position said inking roll is automatically held by said latch means and rendered inactive.
